UNITED STATES PATENT OFFICE.

WILLIAM F. STRAUB, OF CHICAGO, ILLINOIS, ASSIGNOR TO ELECTRIC TIME RECORDER COMPANY, OF CHICAGO, ILLINOIS.

TIME-STAMP.

1,292,135.

Specification of Letters Patent.

Patented Jan. 21, 1919.

Original application filed January 19, 1914, Serial No. 813,132. Divided and this application filed November 13, 1916. Serial No. 121,063.

To all whom it may concern:

Be it known that I, WILLIAM F. STRAUB, a citizen of the United States, residing at Chicago, in the county of Cook and State of Illinois, have invented a certain new and useful Improvement in Time-Stamp, of which the following is a full, clear, concise, and exact description, reference being had to the accompanying drawings, forming a part of this specification.

My invention relates to time stamps and has for its object the provision of an improved arrangement for the controlling and stamping elements of the device together with improved constructional features involving these setting and stamping portions.

This application is a division of my prior Patent No. 1,204,714 issued Nov. 14, 1916.

I will explain my invention more in detail by referring to the accompanying drawings illustrating one embodiment thereof in which—

Figure 1 is a front view partly in section of my improved time stamp;

Fig. 2 is a side view partly in section of the same, and

Fig. 3 is a detail of construction.

I utilize a suitable base plate 1 which is provided with the cup shaped recess 2 and on which a suitable cover plate 3 is mounted, which cover plate is provided with a slot 4 to permit the handle 5 to pass therethrough, which handle is the one used to cause an impression by the time stamp. The base plate 35 has a depressed portion throughout the right half portion of its upper surface (Fig. 2) as shown more clearly at 6, and on top of this a plate 7 is placed which runs throughout the entire length of the top of the base 40 and projects over at 8. A small portion of this plate is cut-away as shown at 9 to permit all of the type wheels and the driving mechanism comprising the stamping device 10 to be depressed upon the top of the base 45 1. It will be seen that there is thus provided a groove as shown at 6 running entirely the length of the machine which is to accommodate the paper or card upon which the impression is to be made. The printing 50 wheels of the stamping mechanism 10 are all to the right of the plate 7 so as to form

the impression upon the paper inserted for receiving the impression.

The impression or stamping device 10 together with the various elements carrying the same and operated by the handle 5 are all mounted on a suitable plate 11 which is laid on top of the plate 7 and then fastened in place through the agency of suitable screws not herein shown. This structure 55 which is designed to cause periodic actuation of the impression device is similar in general arrangement to that disclosed in my Patent No. 1,200,043, issued Oct. 3, 1916. This structure including all this mechanism is 60 mounted between two side walls 12 and 13 and includes a pair of toggle levers 14, 14 and 15, 15 at whose lower extremities the impression mechanism is pivotally carried. The handle 5 actuates this mechanism so as 65 to depress the impression mechanism 10 to cause a rapid impression of the impression device which then recoils automatically so that this impression device cannot be held in its depressed condition. The lower extremities of the toggle members are held 70 together by a shaft 16 and this is also mounted in and carried by a pair of arms 17 pivotally mounted on a shaft 18 fastened in the side members 12 and 13. The arms 17 are spanned by a bridge 19, which bridge 75 normally rests on top of a cam 20 carried by the lever 21 which is fixedly secured to the handle 5. The lever 21 to which the handle 5 is securely fastened is pivotally 80 mounted upon the shaft 21^a. The upper extremity of the toggles 14, 14 are pivotally held upon a shaft 22 secured in the side members. The meeting extremities of the toggle members 14, 14 and 15, 15 are pivotally 85 mounted upon a shaft 23. The shaft 23 is connected by means of a spring 24 to a rocking arm 25 pivotally mounted upon the shaft 18. The arm 21 carries a pivotally 90 mounted cam 26 which impinges against the arm 25 whenever the lever 5 is moved in a clockwise direction (Fig. 2). Whenever the movement of the arm 21 has progressed far enough, then the upper transverse extremity 95 27 of the arm 25 slides upwardly and over the top of this cam 26. Before the arm 25 however is released it has exerted a pull through 100

the agency of the spring 24 upon the shaft 23, thus tending to move this shaft 23 to the right (Fig. 2), and thus depress the impression device 10. This however cannot occur as the bridge 19 rests on the cam 20 until the arm 5 has been moved far enough in a clockwise direction to release the bridge 19, at which time the spring 24 quickly draws the shaft 23 to the right (Fig. 2) and causes an impression upon the card placed in the slot at 6. Immediately thereafter the extension 27 has ridden over the cam 26, thus permitting the arm 25 to be pulled to the left (Fig. 2) through the agency of the spring 24, thus to again permit the shaft 23 to move to the left under the influence of the leaf spring 28. Whenever the handle 5 is moved in a clockwise direction it also moves an arm 29 in a clockwise direction as soon as the arm 21 engages a pin 30 provided on the arm 29. This arm 29 through the agency of the spring 31, partly broken away in Fig. 2, acts on a lever 32, which lever is pivoted to the arm 17 as shown in dotted lines in Fig. 2. This arm 32 carries a cam shaped extremity 33 which is adapted to engage a star wheel 34 forming part of the type wheel mechanism, thus to accurately align a type wheel that may not be in alignment, whenever the arm 5 is first moved to cause an impression. Movement of the arm 32 also causes a swinging movement of the arm 35 because this latter arm is connected by means of a link 36 to the arm 32. This arm 35 carries a roller 37 adapted to engage the star pinions 38 which serve to transmit the movement between the various type wheels.

Thus whenever the arm 35 is so actuated to have its roll 37 engage the star wheels 38 as when an impression is being made, then the controlling mechanism which sets the type wheels is prevented from actuating said type wheels during the time that this impression is being made. A ribbon 39 is provided which is associated with two take up rolls 40 and 41 respectively, each provided with a ratchet 42, 43 respectively. The ribbon also passes about rollers 44, 45, 46 and 47, and thus is carried by under the type wheels as clearly apparent from Fig. 1.

Now whenever an impression is made a bell crank lever 48 is moved in a clockwise direction as its arm 49 is actuated between pins 50 and 51 provided upon the arm 21. This lever 48 pulls a bar 52 downwardly, thereby actuating a lever 53 in a clockwise direction, this lever being pivoted upon the stud 54. The movement of this lever 53 through the agency of the stud 55 and slot 56 causes an up and down movement of a plate 57, which plate carries two pawls 58 and 59 respectively. The pawl 59 is in Fig. 1 shown in engagement with the ratchet wheel 43. Now whenever this plate is

moved downwardly the pawl 59 will engage the ratchet wheel 43 and move the take up roll 41 the distance of one tooth. It will be seen that the pawls are pivotally mounted on arms 60 and 61 respectively and are either held in engagement with their respective ratchet wheels or away from them because the pawls are provided respectively with pins 62 and 63, which pins operate in slots 64 and 65 respectively. These slots are provided in a rocking bar 66 pivoted at 67, which rocking bar has a cam 68. A plunger 69 pushed to the left by the spring 70 is carried in another rocking bar 71, which rocking bar 71 depends for its position upon the thickness of the ribbon upon either take up roll. Should the ribbon be finally wound on the take up roll 41 sufficiently to move the rocking bar 71 in a clockwise direction, then the plunger 69 is moved to the opposite side of the cam 68 and reverses the position of the rocking bar 66, to thereby throw the pawl 58 into engagement with the ratchet wheel 42 and to withdraw pawl 59 from engagement with the ratchet wheel 43. Each movement of the plate 57 will then cause a winding movement of the roll 40 to thus rewind the ribbon upon the roll 40 to such a thickness that a reversal of the parts is again effected, whereupon the roll 41 serves as the take up roll.

The impression mechanism is periodically set by rotating the shaft 72, which shaft then in the customary manner moves the type wheels. This shaft receives its motion from a pinion 73, which pinion through the interposition of pinions 74 and 75 receives its movement from the gear wheel 76. This gear wheel 76 is fastened to a shaft 77, which shaft carries two armatures 78 and 79, which armatures are under the influence of three magnets 80 and cause a setting of these armatures once per minute similarly to the structure explained in my Patent No. 1,200,043.

I mount this driving mechanism to one side of the operating device as shown and thus obtain a very compact simple structure requiring very little intermediate mechanism to transmit the motion directly from the shaft 77 to the time wheels. Parts of the mechanism project into the cup-shaped recess 2 as is clearly apparent from an inspection of Fig. 1. Two gear wheels 74 and 75 are interposed between the gear wheel 76 and the gear wheel 73 so as to avoid movement of the shaft 72 whenever the impression mechanism is actuated as will be clear from the illustrations, as only the gear wheels 74 and 75 need turn, thus permitting the gear wheel 73 to remain stationary except when operated by the driving gear 76.

I have thus described one form which my invention may take and it will be readily apparent that many modifications may be

made without departing from the spirit of my said invention. Having however thus described one form which my invention may take, what I claim as new and desire to secure by Letters Patent is:

1. A device of the character described comprising a base, type wheels movably carried by said base, horological mechanism for periodically setting said type wheels mounted upon said base, toggle mechanism, a manually operated handle for at will operating said type wheels into a printing position, means for causing an automatic recovery of the toggle mechanism after actuation, and means controlled and movable with said handle for alining said type wheels.

2. A device of the character described comprising a base, type wheels movably carried by said base, horological mechanism for periodically setting said type wheels mounted upon said base, toggle mechanism, a manually operated handle for at will operating said type wheels into a printing position, means for causing an automatic recovery of the toggle mechanism after actuation, and

means controlled by and movable with said handle for preventing setting of said type wheels during the printing actuation.

3. A device of the character described comprising a base, type wheels movably carried by said base, horological mechanism for periodically setting said type wheels mounted upon said base, toggle mechanism, a manually operated handle for at will operating said type wheels into a printing position, 30 means for causing an automatic recovery of the toggle mechanism after actuation, means controlled and movable with said handle for alining said type wheels, and means controlled by and movable with said handle for 35 preventing setting of said type wheels during the printing actuation.

In witness whereof, I hereunto subscribe my name this 27th day of October, A. D., 1916.

WILLIAM F. STRAUB.
